(57) **CLAIM**

The ornamental design for a bottle insert, as shown and described.

DESCRIPTION

FIG. 1 is a front perspective view of a bottle insert showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the bottle insert shown with the environment removed for clarity of disclosure;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

In the drawings, the broken lines depict a bottle that forms no part of the claim.

1 Claim, 12 Drawing Sheets
